UNITED STATES PATENT OFFICE.

WILLIAM J. BARBER, OF DELPHOS, OHIO, ASSIGNOR TO THE DELPHOS MOP COMPANY,
OF DELPHOS, OHIO, A CORPORATION OF OHIO.

WRINGER-MOP CONSTRUCTION.

Application filed August 2, 1926. Serial No. 126,428.

This invention relates to floor mops, but more particularly to combined mop and wringer constructions, and an object of this invention is to produce a simple and improved wringer and mop construction which may be cheaply manufactured and efficiently accomplishes the purpose for which it is intended. Further objects and advantages will be pointed out hereinafter.

The invention is shown by way of illustration in the accompanying drawings, in which:

Figure 1 is a side elevation of a combined mop and wringer embodying the invention; Figure 2 is a section on the line 2—2 of Figure 1 showing the wringer construction; Figure 3 is a plan view of the mop frame or head; Figure 4 is an enlarged view of the mop and wringer showing the manner of operating the wringer; Figure 5 is a section on the line 5—5 of Figure 4, and Figure 6 is a section on the line 6—6 of Figure 4.

The illustrated embodiment of the invention comprises a handle 1 of wood or other suitable material having its outer end portion cut away as shown at 2, the under side of the handle preferably being tapered to a blunt point. Fitting over the outer end of the handle is a sleeve 3 which is formed from a strip of sheet metal bent into substantially U-form. Any suitable means (not shown) may be employed in securing the sleeve 3 to the handle.

Extending through the inner part of the sleeve 3 and handle 1 is a wringer crank 4 having a handle 5 at one end and a mop-engaging loop portion 6 at the opposite end. In order to provide an efficient bearing for the crank 4, a piece of metal 7 is fixed to the opposite side of the handle 1 so that one part of the crank bears in the sleeve 3 and another part in the bearing piece 7. For simplicity of manufacture, the bearing piece 7 may be cut or stamped from the sleeve 3 leaving the opening 8, clearly shown in Fig. 4. It will be apparent that by this means a material saving in stock is effected and a reliable mounting for the wringer is provided.

Depending from the forward end of the sleeve 3 are a pair of ears 9 and the adjacent portion of the sleeve is formed with a transverse slot 10. Pivotally mounted in the slot 10 and extending underneath the tapered end of the handle 1 is a link 11 which assists

in holding the end portion of the handle in place. The opposite end of the link 11 is pivoted to a plate 12 which is securely attached to the mop frame or head 13.

The mop head 13 is formed from a single length of wire which is bent to form a triangularly shaped inner end 14, intermediate rods 15 converging toward the opposite end, and an open mop engaging loop 16 at the outer end. By converging the rods 15 toward the loop 16, a decided advantage is obtained because the mop cloth will not slip between the rods 15 when an inward pull is exerted during the wringing operation or while in service.

It will be observed that the plate 12 which serves as a bearing for one end of the link 11 has its opposite sides bent or folded over the inner end portions of the rods 15 and the inner end of the plate is bent over the adjacent part of the triangular loop 14. In this manner a secure connection is effected which not only holds the plate 12 fixedly in place, but also holds the rods 15 in proper relative position.

A mop cloth 17 of the hank or loop pattern is engaged at one end in the wringer loop 6, and at the opposite end in the mop head loop 16. It will be seen that the loop 16 is open so that the mop cloth may be disengaged, and in order to close the opening a latch 18 is pivoted to one portion of the loop to swing across the gap or opening. The latch 18 is of channel shape so as to fit over and frictionally engage the adjacent loop portion. This latch enables the mop cloth to be readily attached to and disengaged from the head.

In use, it will be understood that when the mop frame 13 is pressed downwardly during the mopping operation, the mop cloth being drawn taut and pulling the loop 6 of the wringer so as to position the wringer handle upward, thereby holding the handle close to the mop handle and preventing it from catching in obstructions.

When it is desired to wring the mop cloth, the operator grasps the handle 1 with one hand and raises the mop, whereupon the mop head 13 swings upward at its inner end until the loop 14 engages the ears 9 which serve as stops. The wringer crank 4 may be then revolved and the mop cloth twisted, as shown in Fig. 4.

In most mops of this type the wringer

crank points toward the lower end of the mop handle and as a result it catches on obstructions, for example, it interferes with mopping under radiators and not infrequently the handle gets wet when the mop is put into the pail. To overcome the objections and hold the wringer crank 4 in upwardly pointed position, a spring catch 19 is formed with an upwardly bent end portion 20 which 5 is grooved to engage and releasably hold the crank against accidental movement. The catch 19 is of spring metal and has one end fixed to the mop handle 1 by rivets.

While the wringer mop hereinbefore described is the best form known to me at the present time, numerous changes in details of construction and arrangement may be effected without departing from the spirit of the invention.

20 What I claim as new and desire to secure by Letters Patent is:

1. A combined mop and wringer having a handle, a sleeve secured to the outer end of said handle, a link pivoted to said sleeve, 25 a frame having looped end portions and intermediate rods converging toward the outer loop, a plate having its edges bent around

said rods and the inner loop of said frame and providing a bearing for the opposite end of said link, a wringer crank pivoted to 30 said handle, a mop cloth engaging said wringer crank and the outer loop of said frame, the outer loop of said frame being open and a channel-shaped latch pivoted to said loop and adapted to bridge the opening to enable said mop cloth to be attached to or disengaged from said frame.

2. A combined mop and wringer having a handle provided with a tapered end portion, a sleeve fitting over said tapered end portion, ears depending from opposite sides of the outer end portion of said sleeve, said sleeve and ears being formed with an elongate transverse slot, a wire link having a portion extending through said slot underneath the end portion of the handle, a mop frame, means for pivoting said mop frame to said link, a wringer crank extending thru said sleeve and handle, and a mop cloth engaging one end of said mop frame and said wringer crank.

In testimony whereof I have hereunto signed my name to this specification.

WILLIAM J. BARBER.
